UNITED STATES PATENT OFFICE

GLENN E. COUCH, OF ROCHESTER, NEW YORK, ASSIGNOR TO THE SYMINGTON COMPANY,
OF NEW YORK, N. Y., A CORPORATION OF MARYLAND

CENTERING DEVICE

Application filed February 12, 1927. Serial No. 167,698.

This invention relates to centering devices and, more particularly, to such adapted for association with railway draft rigging for supporting and centering the couplers there-
5 of.

The principal object of my invention is the provision of a centering device for couplers involving links movably supporting an associated carrier block with provision for rock-
10 ably mounting the upper ends of said links and for connecting the lower ends thereof with said carrier block by spaced pivotal connec-
tions which are alternatively operable, whereby said device is more effective for re-
turning the associated coupler to central po-
15 sition.

An object of my invention is the provision of a centering and supporting device for couplers involving swinging links supporting a carrier block extending between the lower ends thereof, the upper ends of said links being mounted for rocking rather than for pivotal movement with respect to an associated coupler stop and sill tie casting.

20 Another object of my invention is the provision of a centering device for car couplers comprising a coupler carrier block swingingly mounted by means of links connected at opposite ends thereof, provision being made whereby, when the block swings to one side, it pivots about a set of trunnions on the links and, when it swings to the other side, it pivots about another set of trunnions on the links so that more effective centering action
25 is obtained.

A further object of my invention is the provision of a centering device for couplers comprising links with T-shaped ends rock-
30 ably mounted in the U-shaped side portions of an associated combination striking casting and sill tie member, the lower ends of links being provided with laterally spaced trunnions and a carrier block formed with bearing notches engaging said trunnions and
35 adapted to pivot on one set of trunnions when swung in one direction and on another set when swung in the other direction, said carrier block extending through apertures in the webs and guided in its motion by said flanges.

A still further object of my invention is the provision of a centering device for couplers comprising a carrier block adapted to support an associated coupler and, in turn, supported at its ends by links rockably 55 mounted on an associated casting adapted for connection at the ends of draft sills, said links being outwardly bowed for permitting greater lateral swinging thereof without engagement with adjacent portions of the cast-
60 ing.

Other objects and advantages of the invention relating to the particular arrangement and construction of the various parts will be-
65 come apparent as the description proceeds.

Referring to the drawings illustrating my invention, the scope whereof is defined by the appended claims:

Figure 1 is a front elevation, partly in section on the line 1—1 of Figure 3, looking in the direction of the arrows, of a combination 70 coupler stop and sill tie casting involving a centering device embodying my invention.

Figure 2 is a plan of the carrier block of my centering device, one of the associated links being shown in section on the line 2—2 of Figure 1 looking in the direction of the ar-
75 rows.

Figure 3 is a side elevation of the embodiment of my invention illustrated in Figure 1, 80 showing the same connected with associated sills and with an associated coupler shown diagrammatically by dot and dash lines.

Referring to the drawings in detail, like parts being designated by like reference char-
85 acters, I have illustrated a combined casting 1 comprising a coupler stop or striking portion 2, depending side portions 3 and a carrier iron or sill tie portion 4 connecting the lower ends of said side portions 3. The coupler striking portion 2 preferably comprises a front or outer upright web 5 serving as a stop for the associated coupler 6 indicated diagrammatically by dot and dash lines, a rearwardly ex-
90 tends web or shelf portion 7 adapted for connection with the associated cover plate 8 and end sill 9 by rivets 10 or the like and a lower web portion 11 framing the opening 12 through which the stem of the coupler 6 ex-
95 tends. For bracing the webs 5, 7 and 11 to-
100

gether, longitudinally extending webs or gussets 13 are preferably provided which taper rearwardly to merge with the web 7 and, more particularly, with the downwardly offset portion 14 thereof which underlies the cover plate 8.

The depending portions 3 are preferably generally channel shape in cross section with webs 15 defining generally the opening 12 through the casting 1 and outwardly extending flanges 16. The outer or front flanges 16 may, if desired, extend inwardly beyond the webs 15 forming rib or lip portions 17 at the outer end of the opening 12. The coupler carrier or sill tie portion 4 is preferably generally inverted U or channel shape in cross section with an upper web 18 and flanges 19 on either side thereof, said flanges being practically continuations of the flanges 16, that is, they merge with said flanges at the adjoining ends thereof and, preferably lie in the same planes. The web 18 is preferably downwardly bowed at its intermediate portion, thereby providing a greater size for the opening 12 for the insertion or removal of the coupler and draft gear and particularly the butt of a coupler of the swivel butt type, such as diagrammatically shown, in which the dimensions thereof are greater than those of the connecting stem. The end portions or those generally underlying the U-shaped portions 3 may be generally flat as illustrated.

The webs 15 of the depending portions 3 are preferably extended rearwardly to provide bifurcated webs or ears 20 for connection with associated sills 21. In the present embodiment, the ears 20 are formed with slots 22 and the sills 21 are slotted to the ends, said ears 20 thereby serving as the forward portions of cheek plates and adapted to cooperate with the usual form of key, the forward portion of a complementary cheek plate being indicated at 23. Said ears or web portions 20 are preferably connected to the sills 21 by a plurality of rivets 24.

In order to provide for supporting the centering device which involves a carrier block 25 and supporting links 26 therefor, the webs 16, adjacent the upper portion thereof, are preferably formed with shelf portions 27 extending toward each other, said shelf portions preferably also merging with the corresponding webs 15 and braced with respect to the flanges 16 by lower gusset portions 28 and by web portions 29 laterally spaced from the web portions 15 to provide pockets 30. The links 26 are preferably formed with rocker or trunnion portions 31 extending longitudinally to engage the lip or shelf portions 27, the lower surfaces of said portions 31 being preferably curved and adapted to rock on said shelf portions 27 rather than pivot with respect thereto. For this purpose, the rocker portions 31, which form T-shaped upper ends on the links 26, are formed small enough

so that sufficient clearance for rocking purposes in the pockets 30 is provided.

The lower ends of the links 26 are likewise generally T-shaped but, instead of having extensions forming rockers as at the upper ends, the extensions 32 each comprise a plurality of laterally spaced trunnion or journal portions 33 supporting thereon the carrier block 25 which is preferably bifurcated at each end to embrace the lower ends of the links 26 and be movably supported thereon by the extensions 32. The bifurcated portions 34 of the carrier block are each preferably provided with a plurality of notches or bearing portions 35 corresponding generally in location and curvature with the trunnion portions 33 of the links, whereby said carrier block is supported for sidewise swinging and, adapted to pivot, when swung in one direction, on one set of trunnions and, when swung in the other direction, on the other set of trunnions, to provide an immediate returning force of substantial amount when said block and its supported coupler are moved from central position, as will be understood. In order to permit insertion of the carrier block 25, the webs 15 are apertured as indicated at 36 and said block is guided and prevented from undesired movement longitudinally of the car by means of the webs 16 which lie on either side thereof with only normal clearance therebetween. In order to permit a relatively large amount of swinging movement of the coupler, especially if a coupler of the swivel butt type is employed, the links 26 are preferably curved or bowed outwardly as indicated at 37 thereby providing a greater clearance with respect to the webs 15.

It will be seen that the engagement between one end of the carrier block 25 and the corresponding link involves outer lip portions 38 which depend to substantially the lower level of said block, whereby engagement between said link and block is relatively secure. The connection at the other end of the block with its associated link preferably involves the use of a generally U-shaped retainer or hairpin cotter 39 with the intermediate portion 40 thereof corresponding in location with the lips 38 of the other end, the side portions 41 extending upwardly through corresponding apertures 42 in the bifurcated portions 34 of the block 25, said retainer or cotter being held in place by having the ends bent over on to the notched portions 43 of the carrier block 25. It will be seen that this construction securely connects one of the links 26 and the corresponding end of the block 25, thereby absolutely preventing them from becoming disconnected when the car is turned over. Even though the other end of the carrier block, which is not absolutely connected by means of a cotter 39, should become slightly sepa-

rated from the corresponding link 26 upon overturning the car, yet, by having the other end held in place by the cotter, engagement would again be effected upon righting the car. Centering of the coupler 6 with respect to the carrier block 25 may be provided in any desired manner as by means of upstanding lugs 44 lying on either side of the coupler, or by having the supporting surface or web 45, for said coupler lying below the upper edge of the end portions 46 of the flanges 47, or both, as illustrated.

A preferred method of assembling the parts of the centering device is as follows. 15 The coupler is first received in the aperture 12 of the casting 1; then the carrier block 25 is inserted into place through the apertures 36, the link 26, at the right or that not connected to the block by means of a cotter is 20 then inserted in place and moved to proper position and the block mounted thereon as illustrated. The other link 26 is then inserted in place and moved to proper position with respect to the block 25, the hairpin cotter 39 inserted from below, the upper ends bent over as illustrated and the mechanism is assembled.

By virtue of the aforescribed construction, it will be appreciated that I have devised a centering device which not only eliminates friction by having a rocking instead of a pivotal mounting for the tops of the links 26 but a greater returning or centering force is provided for the coupler by virtue of the pivotal connections between the bottoms of the links and the carrier block, which connections are alternatively operable depending upon whether the coupler and block are swung one way or the other, as will be understood. It will be appreciated that not only is a greater returning force provided by this construction but this force becomes immediately operable upon disengagement between one of the sets 40 of trunnions 33 and the carrier block as said trunnions are preferably normally spaced on either side of the vertical center line of the bearings at the upper ends of the links. The rocking between the upper 45 ends of the links and the casting, by moving the point of engagement therebetween in a direction opposite to that in which the carrier block swings, augments the returning force provided by the centering device as 50 will be appreciated.

Although the lower portions of the links 26 are shown as provided with outstanding trunnion portions formed as laterally spaced trunnions on either side of said links, yet I do 55 not wish to be limited to such construction as, if desired, a single trunnion at each side of each link may be employed with the upper surface thereof flattened. That is, the configuration of each trunnion portion 32 could, instead of corresponding to a pair of spaced

semi-cylindrical surfaces, be formed flat on top with curved sides and substantially the same effect would be secured as far as the returning moment for centering the supported coupler is concerned. If such a construction were provided, of course, the carrier block 25 would be correspondingly modified in that, instead of providing a plurality of spaced bearing portions 35 in each bifurcated portion of the block, a single relatively long notch or bearing portion, corresponding to the bearing portions 35 with the dividing or separating lug therebetween removed, would be formed in the carrier block. 70 In other words, an equivalent construction for certain purposes and one within the scope of the present invention involves the employment of flattened bearings between the carrier block and the links rather than laterally separated bearing portions as illustrated. 75

Having now described my invention, I claim:

1. A centering device for couplers comprising a member formed with side walls and supporting ledges on either side of an associated coupler, a link disposed outside of the corresponding side wall on either side of said coupler and formed with extensions rockably engaging said ledges, the intermediate portions of said links being displaced from lines joining the ends away from each other to increase the clearance with respect to said side walls and corresponding permissible swinging movement thereof, and a carrier block movably supported from the lower 95 portions of said links.

2. A centering device for couplers comprising a casting having a central passage for the stem of a coupler, said casting being formed, on either side of said coupler, with flat supporting shoulders, a link at each side of said coupler formed with extensions adjacent the upper end thereof with curved surfaces engaging said shoulders for rocking movement thereon, the lower end of each link being formed with a plurality of transversely spaced trunnion portions, and a carrier block movably supported on said trunnion portions of the link and adapted to pivot alternately about the same, the element of said casting defining the lower outline of said passage being disposed below the lower edge of said block so that removal of the latter enlarges the passage to permit the insertion or removal of a coupler with a relatively 110 large butt.

3. A centering device for couplers comprising a member formed with supporting ledges on either side, a link formed with extensions rockably supported on said ledges on either side of an associated coupler, the lower ends of said links being formed with outwardly extending trunnion portions, a carrier block adapted to support an associated coupler and formed with bifurcated ends embracing the 115

lower portions of said links and supported on said trunnion portions and means connecting one end of said block with the corresponding link for preventing disengagement of the carrier block when the car is turned over.

4. A centering device for couplers comprising a member formed with a web and supporting ledge on either side, a link disposed to one side of the adjacent web on either side and formed with an extension swingingly engaging the corresponding one of said ledges, and a carrier block movably supported from the lower portions of said links, said links being bowed away from the adjacent webs to permit greater swinging movement thereof.

5. A centering device for couplers comprising a center casting having a passage therethrough for the stem of a coupler, the side portions of said casting being generally U-shaped in cross section with the webs of said U's inwardly disposed and the flanges extending outwardly, shelf portions on said flanges extending toward each other and providing bearings, links movably supported at their upper ends by means of said shelf portions, the lower ends of said links being formed with trunnion means, the lower portions of said webs being apertured and a carrier iron inserted through said apertures, guided by said flanges and movably carried on the trunnion means of the links, the lower element of said center casting being bowed downwardly below the carrier iron to provide a passage of relatively great depth to permit the insertion or removal of a coupler with relatively large butt, upon removal of the carrier iron.

6. A centering device for couplers comprising a casting adapted for connection with the ends of associated sills and formed with an aperture for receiving the stem of an associated coupler, those portions of the member, on either side of said aperture, being each provided with a shelf portion adapted to movably support a carrier link, carrier links formed with bearing means engaging said shelf portions and depending therefrom, the lower ends of said links being formed with trunnion means and a carrier block supported on said trunnion means and guided by said casting, the lower member of the casting defining the coupler receiving opening being downwardly spaced with respect to the block.

7. A centering device for couplers comprising a casting formed with an upper coupler stop portion, depending side portions generally U-shaped in cross section and a sill tie portion connecting the lower ends of said side portions, ledges provided on the flanges of said U-shaped portions and extending toward each other, link means mounted between said flanges and formed

with extensions at their upper ends engaging said ledges and adapted to rock thereon, the lower ends of said links being formed with lateral extensions providing a plurality of trunnion means at either side of each link and a carrier block bifurcated at its ends and embracing the lower ends of said links, each of said portions, on opposite sides of said links, being formed with a plurality of correspondingly spaced bearing pockets engaging said trunnions on the links, whereby, upon motion of the carrier block, pivotal motion takes place alternately with respect to said trunnions, said sill tie portion being curved downwardly below the carrier block from its ends towards its center to provide a passage of relatively great depth to permit the insertion or removal of a coupler with a relatively large butt upon removal of the carrier block.

8. A centering device for couplers comprising a member formed with a supporting ledge on opposite sides of an associated coupler, a link on either side of said coupler rockably supported on said ledge, a carrier block provided with a bearing portion at each end thereof, said links being formed with corresponding trunnion portions engaging in said bearing portions of the block for pivotally connecting said members, each of said bearing and trunnion portions involving parts curved about spaced centers, whereby the pivotal movement between said links and carrier block takes place about changing centers, one end of said block having lip portions hooking over the corresponding trunnion portions of the associated link, and retainer means for preventing undesired separation of the other end of said block from the other end of its link.

In testimony whereof I affix my signature.
GLENN F. COUCH.
